UNITED STATES PATENT OFFICE

2,476,563

SHIP'S PORTABLE BATTEN CLIP

Carl W. Pirl, Long Beach, and Kazmier L. Holody, Los Angeles, Calif.

Application February 3, 1945, Serial No. 575,970

4 Claims. (Cl. 189—34)

1

This invention relates to improvement in ships' portable batten clips, and the objects of said improvements are: (1) to keep portable battens in a locked and secured position at all times in case of underwater explosions or from other forces which may act upon them, (2) to provide a clip which is self locking and always remains in a set position, (3) to enable the removal or installation of portable battens more quickly and easier.

Other objects of the invention are to provide a device of the aforementioned character which will be strong, durable, highly efficient and reliable in use, and which may be manufactured at low cost.

Other important objects and advantages of the invention will be apparent from a reading of the following description taken in connection with the accompanying drawing forming a part of this specification.

Referring to the accompanying drawing, which illustrates what is at present deemed to be a preferred embodiment of the invention:

Fig. 1 is a longitudinal cross section on line 1—1 of Fig. 3, looking in the direction indicated by the arrows.

Fig. 2 is a transverse sectional view on line 2—2 of Fig. 3 looking in the direction indicated by the arrows.

Fig. 3 is a complete plan view of the device shown in Fig. 1, the batten being shown in cross section.

Fig. 4 is a part reproduction of the longitudinal cross section of Fig. 1 showing the dog plate of the portable batten clip in an open position.

Fig. 5 is a side elevation on a reduced scale of the complete unit as installed in general use.

Fig. 6 is a side elevation of the unit shown in Fig. 5.

Referring in detail to the drawing, the batten proper 4 is shown held in place at its upper end by an angular bracket 5 attachable to a ceiling, and at its lower end by a sheet metal clip 1 attachable to a floor. The lower portion of the bracket 5 is suitably apertured to receive loosely the upper part of the batten 4, and the clip 1 is of an inverted U-shape and has a horizontal upper part 1a furnished with an opening 1b which loosely receives the lower end portion of the batten. There is enough clearance between the upper end of the batten and the ceiling to allow the batten to be lifted clear of the clip 1 during installation and removal.

The batten 4 which may be variously designed as to its cross-sectional contour and construc-

2

tion, without exceeding the scope of the claimed combinations, is shown as consisting of sheet metal which is bent to the shape of a rectangular C as viewed in cross section, there being shown an aperture 4c in its lower end portion with which cooperates a dog plate 2 swingably supported by a pivot pin 3, said pin being secured in any convenient manner to the lower side of the clip wall 1a and underlying the slot 1d in which the dog plate 2 swings. Said slot occupies an upper corner portion of the bottom clip 1 and has a lower edge portion 1f positioned to arrest the down-swing of the outer portion of the dog. Said dog has a downwardly projecting stop extension 2a positioned to arrest the anti-clockwise swing of the dog when the latter reaches the released position shown in Fig. 4. Said dog is a plate of a generally semicircular shape, said stop projecting from its straight edge and occupying a space between the batten and the adjacent end wall of the clip. The dog is shown having a pointed nose portion 2b. The pivot 3 is located nearer the nose portion of the dog than to its opposite corner portion, so that the dog, when left free to do so, will automatically gravitate to the locked position, shown most clearly in Fig. 1.

In operating the device the portable batten is installed simply by pushing it into the cut-out in the overhead clip 5 and then bringing it down and pushing it into the clip 1. Doing this will push the hinged dog plate 2 down until the slot 4c in the batten is reached by the dog's nose. At this moment the dog plate 2 will automatically fall into the correct position and lock the portable batten in 4 in place. The portable batten 4 can have slots on each side and on each end. In this case a portable batten can be picked up and put in place without looking for the right end and side. This will enable one to install portable battens without hesitation.

To remove portable batten 4 the workman will lift up the hinged dog plate 2 by the bottom overhanging straight edge, either by hand or by his foot, and then pull upon the batten. When the portable batten 4 is out and the dog plate 2 released, the latter will automatically fall in the correct position ready for the insertion of the batten 4 when required.

We claim:

1. In a structure of the kind described the combination with a ship's batten having a lower end portion provided in at least one of its sides with an aperture providing an upwardly directed shoulder, a clip for said batten attachable to a deck of

the ship, said clip having a sheet metal top portion provided with an aperture loosely to receive said batten, said aperture having a lateral extension partially located in an upper corner portion of said clip and providing a stop shoulder, a dog pivotally mounted in said extension of said aperture, said dog being of a plate-like structure and having at one side of its pivotal mounting a nose to extend into said aperture of the batten and overlie said shoulder of the batten to lock the latter in its mounted relation to the clip, the portion of the dog at the side of its pivotal mounting opposite its nose at such time resting upon and projecting beyond said stop shoulder, said projecting portion of the dog affording a downwardly facing operating shoulder for manually swinging the dog to a released relation to the aforesaid shoulder in the batten.

2. In a device of the kind described, a clip having a basal portion attachable to a deck or floor and an upper portion with an aperture to receive removably a batten in an upstanding position, and a gravity operable dog pivotally mounted upon said clip, said dog consisting of a generally semicircular plate having at one end of its arcuate side a nose portion, the dog tending to gravitate to a position wherein the end or side portion thereof opposite to said nose rests upon and projects beyond a side portion of said clip, thereby maintaining said nose portion positioned to prevent withdrawal of the batten from the clip, the projecting portion of the dog being manually accessible to enable the operator to rock the dog against gravity to a release position, said dog having a stop projection positioned to engage internally the aforesaid side portion of the clip to limit the swing of the dog when it reaches a released position.

3. In a structure of the kind described, in combination, a ship's batten having a lower end portion provided in at least one of its sides with an upwardly directed shoulder, a sheet metal clip of an inverted U-shape for said batten attachable to the deck of a ship, said clip having end walls and a top wall provided with an aperture loosely to receive the batten, said aperture being spaced inwardly from an end wall of the clip,

and a dog pivotally mounted upon said clip at a point below said top wall thereof, said dog at least in part occupying the space between said batten and said end wall of said clip, there being a vertical slot through said end wall of the clip the lower end of which forms a stop on which at times rests an end portion of said dog which projects from the clip, the opposite end portion of said dog at such times being superjacent to the aforesaid shoulder of the batten to lock the batten in place, that end portion of the dog which projects through the slot in the clip being at such times manually accessible for swinging the dog to an unlocked position.

5 4. In a structure of the kind described, in combination, a ship's batten having a lower end portion provided in at least one of its sides with an upwardly directed shoulder, a clip structure attachable to the deck of a ship to receive the lower end portion of said batten, said clip structure including a part having in it a slot which lies in a vertical plane, a plate-like dog pivotally related to said clip in a position to swing in an edgewise manner within and longitudinally of said slot, said dog having a nose portion at one side of its pivot positionable above said shoulder of said batten to lock the latter in place, said dog when in such locking position having its opposite end portion supported by an upwardly directed shoulder formed by an end portion of said slot, said dog being swingable against the opposition of gravity to a position wherein its said nose portion is in a released position in relation to said shoulder of the batten.
